UNITED STATES PATENT OFFICE.

TRAUGOTT PAUL KRUGER, OF NEW YORK, N. Y.

ERASER-HOLDER.

1,028,034.

Specification of Letters Patent. Patented May 28, 1912.

Application filed April 13, 1910, Serial No. 555,167. Renewed September 6, 1911. Serial No. 648,129.

To all whom it may concern:

Be it known that I, TRAUGOTT P. KRUGER, a citizen of the United States, and a resident of the city of New York, borough of 5 Manhattan, in the county and State of New York, have invented a new and Improved Eraser-Holder, of which the following is a full, clear, and exact description.

The object of the invention is to provide 10 a new and improved eraser holder, arranged to accommodate an eraser strip for ink, or one for pencil, or for both, one at each end of the holder, to securely hold the eraser strip in position in the holder, and to permit 15 of quickly and conveniently adjusting the eraser strip in the holder, to project the strip the desired distance from the end of the holder, to allow a proper and economical use of the eraser strip. For the purpose 20 mentioned, use is made of a hollow handle, for the reception of an eraser strip, and a locking and ejecting device mounted on the said handle, near the end thereof and engaging the eraser strip, to lock the same in 25 place in the holder.

A practical embodiment of the invention is represented in the accompanying drawings forming a part of this specification, in which similar characters of reference indicate corresponding parts in all the views.

Figure 1 is a perspective view of the eraser in use; Fig. 2 is an enlarged cross section of the same; Fig. 3 is a like view of the same, showing the locking device in 35 open position and the eraser strip removed; and Fig. 4 is a sectional plan view of the eraser on the line 4—4 of Fig. 2.

The handle A, shown in Figs. 1 and 2, is made hollow and open at both ends, to 40 accommodate two eraser strips B and B', of which one is for erasing pencil marks and the other for erasing ink marks, the strips being projected beyond the corresponding ends of the handle A and locked in place 45 therein by locking levers C, located near each end of the handle A. Each locking lever C consists of parallel arms C' fulcrumed on a pivot D, preferably in the form of a piece of wire, encircling the handle A 50 and extending in an annular groove thereof, so as to project but little from the surface of the handle A. The arms C' of each lever are connected with each other at their free ends by a finger piece C², and on the fulcrum or pivotal ends of the said arms C'

are formed teeth C³, adapted to pass through slots A', formed in the handle A, so that the teeth project inside of the handle and impinge or embed themselves in the corresponding eraser strip B or B', as 60 plainly indicated in Figs. 2 and 4. Now when the lever C is swung into open position, as shown in Fig. 3, then the bore of the handle A is unobstructed to permit the convenient insertion or removal of a corresponding eraser strip B or B', and when an eraser strip has been inserted a desired distance, then the user swings the lever C into a closed position, whereby the teeth C' 65 engage the eraser strip and embed themselves in the same, at the same time drawing the eraser strip inward until the finger piece C² rests against the outer face of the handle A, thus limiting the swinging motion of the lever C. 70

By the arrangement described, the outer end of the eraser strip B or B' may be projected any desired distance from the end of the hollow handle A, to permit of conveniently using the eraser for erasing purposes. When the projecting end of the eraser strip has become too small for proper erasing purposes, then the operator takes hold of the finger piece C² and swings the same outwardly, and in doing so the teeth 80 C³ push the eraser strip B or B' outward, to permit the user to conveniently take hold of the outer end of the said strip, to draw the latter farther outward in the hollow handle A. When this has been done, the 85 lever C is again swung into closed position, whereby the eraser strip is drawn a short distance inward, to project the outer end thereof the desired distance from the corresponding end of the hollow handle A. 90

It is understood that the harder the pressure against the outer end of the eraser strip when using the device, the tighter the lever C will be drawn into closed position, to insure a very secure and firm hold of the 95 eraser strip in the hollow handle A.

The eraser holder shown and described is very simple and durable in construction, is composed of but few parts, and assembled so as not to become disconnected and loose. 100 It will further be understood that by the arrangement described each eraser strip can be used up almost to the very inner end, and hence renders the device economical in 105 the use of the eraser material used for the 110

purpose. It will also be seen that a new eraser strip can be readily placed in position in the holder whenever desired.

Having thus described my invention, I 5 claim as new and desire to secure by Letters Patent:

A device of the character specified, comprising a tubular holder provided with spaced substantially parallel longitudinal 10 slots near one end, a ring encircling the holder at said end and passing transversely of the slots, the outer face of the holder being annularly grooved to receive the ring, a lever pivoted on the ring in each of the 15 slots, each of the said levers having a plurality of teeth extending through the slots

for the purpose specified, and a handle for each lever outside of the slots, the handles being connected with each other, the handle and the teeth of each lever being at substantially a right angle with respect to each other, so that when the teeth are in engagement with the eraser the handles will lie flat on the outer face of the holder. 20

In testimony whereof I have signed my 25 name to this specification in the presence of two subscribing witnesses.

TRAUGOTT PAUL KRUGER.
